UNITED STATES PATENT OFFICE.

WILLIAM I. BUNKER, OF LA GRANGE, ILLINOIS.

DESIGN FOR A CUSHION FOR SOLES.

SPECIFICATION forming part of Design No. 29,749, dated November 29, 1898.

Application filed September 16, 1898; Serial No. 691,113. Term of patent 14 years.

To all whom it may concern:

Be it known that I, WILLIAM I. BUNKER, of La Grange, Cook county, Illinois, have invented and produced a new and original Design for Cushions for Soles, of which the following is a specification.

In the accompanying drawings, Figure 1 is a plan view of the cushion of a shoe, presenting my design; Fig. 2, the same looking at it from the bottom, and Fig. 3 a longitudinal sectional view taken on line 3 of Fig. 1.

In the drawings, A is the cushion, C the ribs of the cushion, and D vertical cells or spaces formed by the ribs.

The leading feature of my design consists of a sole provided with a cushion having ribs integral with each other, forming vertical cells or spaces, the whole presenting an attractive and ornate appearance, as shown in the drawings.

I claim—

The design for a cushion for soles as herein shown and described.

WILLIAM I. BUNKER.
